UNITED STATES PATENT OFFICE.

JOSEPH BAER, OF CHICAGO, ILLINOIS.

POWDER PUFF AND PROCESS OF MAKING THE SAME.

Application filed April 10, 1926. Serial No. 101,080.

Heretofore in making powder puffs circular pieces of cloth have been cut out and sewed together around the edges with the sides that were to be outside when the articles were completed facing or in contact with each other, so that the sewing was done wrong side out. In making such powder puffs a short unsewed portion was left through which the pieces could be turned 10 to bring the right side out and to bring the seam on the inside so that the smooth side of the cloth could come into contact with the user's face and the seam would be hidden. Ribbon or a strap to form a handle 15 was laid diametrically across the pieces between them before they were sewed together, thus causing the ends of this ribbon or strap to be sewed in place and to lie on the outside when the article was turned through 20 the unsewed space. A layer of filling, such as cotton or the like, of proper shape was usually attached to the outside of one of the pieces before the pieces were turned, so as to bring their prior contacting sides on 25 the outside and the filling material on the inside. The exposed edges of the unsewed portion were then turned inward and the hole sewed up by hand. This operation required great care as the edges were folded 30 into the unsewed space such a short distance that it was difficult to hold the parts in place while they were being sewed, and it was also difficult to complete the sewing along the correct circular line. Also, in 35 placing two circular pieces of cloth together preparatory to sewing them, it frequently happened that the threads in the respective pieces that constituted the puff were not parallel to each other, and, since arcuate portions 40 between diametrical threads stretch more easily than arcuate portions near the ends of diametrical threads, puckers were apt to occur at different positions around the circumference. Besides, the ribbon or 45 strap that was attached to form a handle was often located so that it laid diagonally across the warp or woof threads of the cloth, imparting to the completed article the appearance of being distorted or not exactly 50 circular. By the present invention former difficulties and objections are overcome in making powder puffs, the article is improved in appearance, and the process of making the same is more satisfactory. In carrying 55 out this invention, circular pieces of cloth are cut out leaving a tab on each piece that

has heretofore been wasted, in cutting out the pieces. These tabs aid in the operation of sewing the pieces together after the article is turned right side out. They also not 60 only serve as guides to enable the pieces to be laid together properly preparatory to sewing so as to avoid the formation of puckers, due to uneven stretching of contacting portions, but also serve as guides to 65 enable the cross ribbon or strap to be correctly located in place, parallel to the warp or woof threads, so as to avoid a distorted appearance of the completed article.

The invention will be understood from 70 the description in connection with the accompanying drawings, in which Fig. 1 is a plan view showing how the pieces of cloth can be cut out; Fig. 2 is a plan view showing a step in the manufacture; Fig. 3 is a 75 section along the line 3—3 of Fig. 2 and Fig. 4 is a similar section through the completed article. In the drawings, reference character 6 indicates a piece of cloth from which the circular pieces to form the powder puffs are to be cut. In this figure the lines 7 represent warp threads of the cloth and lines 8 represent woof threads of the cloth, only a few of these lines being shown 80 in order to avoid confusion. The circular pieces 9 are cut from the cloth by dies, or in any other convenient manner, as shown in Fig. 1, in the shape of circles having tabs 10 extending from each one, these tabs being composed of the cloth between the edges 85 of circular pieces adjacent to the one containing the tab. Heretofore, all the triangular pieces between the circles have been thrown away, but as will be obvious from Fig. 1, half of the triangular pieces constitute the tabs for the circular pieces, as just explained, and are left integral therewith. The other triangular pieces as indicated by the cross marks are thrown away 90 as has heretofore been the practice. The 95 circular pieces 9 are advantageously cut from the cloth in such a manner that the tabs 10 thereof are parallel to either the warp or the woof lines in the cloth.

After the circular pieces 9 have been cut 105 from the cloth with the tabs 10 attached, two of these pieces 9 and 9' are laid together with the tabs superposed upon each other and the smooth sides of the cloth facing each other, with a ribbon or strap 13, which 110 may be slightly longer than the diameter of the circular pieces, laid diametrically be-

tween the same at right angles to the tabs 10 and 10', as shown in Figs. 2 and 3. It will be clear, therefore, that the ribbon or strap will be parallel either to the warp or woof threads, as it is at right angles to the tabs 10 which are parallel to the woof or warp threads, and as the tabs are so very much more easily visible than the warp or woof threads, the ribbon or strap 13 can be placed correctly without trouble. At the same time, the portions of the edges that will stretch more are laid together, as well as the portions that stretch less, so that puckering is avoided.

15 After two of the circular pieces have been laid together with the ribbon therebetween, a layer or pad of filling material 14 may be placed on one of the circular pieces 9 and the two circular pieces, the ribbon and the pad may be sewed together, as indicated by the stitches at 12, leaving an unsewed space near the tabs through which the article can be turned or reversed. The article is then reversed by turning the same through the unsewed portion, thus bringing the ribbon 13 on the outside, and the filling material 14 on the inside, as shown in Fig. 4. The projecting tabs 10 and 10' are then turned inwardly and the sewing is completed as indicated at 15. In view of the fact that the tabs 10 and 10' are of considerable length, the operator finds less difficulty in keeping the cloth in place while the hole is being sewed, than is the case with the short turned edges heretofore used.

I claim:

1. The process which comprises cutting out circular pieces of cloth with a tab on each piece, sewing two of such pieces of cloth together near the edge leaving an unsewed portion adjacent said tabs, turning said pieces through said unsewed portion and turning said tabs inside.
2. The process which comprises cutting out circular pieces of cloth with a tab on each piece, sewing two of such pieces of cloth together near the edge leaving an unsewed portion adjacent said tabs, turning said pieces through said unsewed portion and turning said tabs inside and completing the sewing of said pieces together adjacent said tabs.
3. The process which comprises cutting out circular pieces of cloth with a tab on each piece, sewing two of such pieces of cloth together near the edge leaving an unsewed portion adjacent said tabs, turning

said pieces through said unsewed portion and turning said tabs inside and completing the sewing of said pieces together adjacent said tabs with said tabs inside.

4. The process which comprises cutting out circular pieces of cloth with a tab on each piece extending parallel to threads in the cloth, sewing two of such pieces of cloth together near the edge leaving an unsewed portion adjacent said tabs, turning said pieces through said unsewed portion and turning said tabs inside.

5. The process which comprises cutting out circular pieces of cloth with a tab on each piece extending parallel to threads in the cloth, sewing two of such pieces of cloth together near the edge leaving an unsewed portion adjacent said tabs, attaching the ends of a cross strap ninety degrees from said tabs, turning said pieces through said unsewed portion and turning said tabs inside.

6. The process which comprises cutting out circular pieces of cloth with a tab on each piece extending parallel to threads in the cloth, sewing two of such pieces of cloth together near the edge leaving an unsewed portion adjacent said tabs, attaching the ends of a cross strap between said pieces ninety degrees from said tabs, turning said pieces through said unsewed portion and turning said tabs inside.

7. The process which comprises cutting out circular pieces of cloth with a tab on each piece, sewing two of such pieces of cloth and a corresponding layer of filling material together along the edge leaving an unsewed space, and turning the pieces and filling material through said unsewed space.

8. A powder puff comprising circular pieces of cloth sewed together with the seam on the inside more than half way around the edge and tabs projecting inwardly along the remainder of the edge.

9. A powder puff comprising circular pieces of cloth sewed together with the seam on the inside substantially five-sixths of the way around the edge and tabs projecting inwardly along the remainder of the edge.

10. A powder puff comprising circular pieces of cloth sewed together with the seam on the inside more than half way around the edge and tabs projecting inwardly along the remainder of the edge, and a strap approximately ninety degrees from said tabs.

JOSEPH BAER.
